UNITED STATES PATENT OFFICE.

WILLIAM W. MURPHEY, OF LOUISVILLE, KENTUCKY.

WASHING-MACHINE.

SPECIFICATION forming part of Letters Patent No. 732,105, dated June 30, 1903.

Application filed June 23, 1902. Serial No. 112,894. (No model.)

To all whom it may concern:

Be it known that I, WILLIAM W. MURPHEY, a citizen of the United States, residing at Louisville, in the county of Jefferson and 5 State of Kentucky, have invented a new and useful Washing-Machine, of which the following is a specification.

This invention relates generally to washing-machines, and more particularly to that 10 class thereof known as "suction-machines," in which the water is forced alternately in opposite directions through the clothes, thus thoroughly cleansing them without the use of rubbers or pounders commonly employed 15 to effect the same operation.

The invention consists in the novel features 20 of construction and combination, all of which will be fully described hereinafter and pointed out in the claims.

25 In the drawings forming part of this specification, Figure 1 is a perspective view illustrating a washing-machine constructed in accordance with my invention and showing the practical application of the same. Fig. 2 is 25 a longitudinal sectional view of the same. Fig. 3 is a sectional view of one of the cylinders. Fig. 4 is a transverse section on the line 4 4 of Fig. 3. Fig. 5 is a detail sectional view of one of the suction-heads.

30 In carrying out my invention I employ a base-board A, mounted upon a suitable central support A', the board projecting beyond the central support at each side, so that a tub B can be arranged beneath each projecting end 35 of the base-board A. A cylinder C is arranged upon suitable brackets C', attached to the base-board adjacent to the opposite ends, and pivoted centrally upon the base-board is a vibrating hand-lever D, slotted longitudinally, as shown at D', to receive a cross-pin E', carried by the piston-rod E, which works through the heads of the cylinder C, said piston-rod having a piston F at each end. Thus 40 each cylinder is provided with a piston F, and each piston has openings F' and flap-valves F², which are adapted to close the said openings at certain times. A suction-pipe G is connected to the outer end of each cylinder C, and the check-valve H is arranged between 45 the end of said pipe and the head of the cylinder for the purpose of checking the return

of the water sucked into the cylinder through the pipe G. Perforated suction-head I is arranged upon the end of each suction-pipe G, and these suction-heads I are adapted to rest 55 upon the top of the clothes contained within the tubs B. A water-supply pipe K is connected to each cylinder at the end opposite the suction-pipe, and each supply-pipe K leads to the bottom of the oppositely-disposed 60 tub, so that the water sucked into the cylinder from one tub is discharged through the pipe K into the opposite tub. It is obvious from the arrangement of the flap-valves upon the piston and the check-valves at the ends 65 of the suction-pipes that at each stroke of the piston water will be drawn up through the suction-pipe G into the cylinder C. At the same time the water within the cylinder is forced out through the discharge-pipe K into the 70 opposite tub, so that upon the return stroke of the piston the water from the opposite tub will be drawn up through the opposite suction-pipe, and these operations are continued until the clothes are thoroughly cleansed, a 75 continuous circulation of the water through the clothes being obtained.

A check-valve L is arranged at the upper end of each supply-pipe K to prevent the water being drawn back into the cylinder upon 80 the return stroke of the piston.

It will thus be seen that I provide an exceedingly cheap, simple, and efficient construction of washing-machine which will thoroughly cleanse the clothes contained in two 85 tubs or receptacles and without the aid of pounders, rubbers, or agitators.

Having thus fully described my invention, what I claim as new, and desire to secure by Letters Patent, is—

1. In a washing-machine, the combination with a suitable base, of cylinders mounted on opposite ends thereof, a piston working in each cylinder, a slotted lever pivoted between the cylinders, a piston-rod extending between the two pistons and passing through the slotted lever, pins on the piston-rod adapted to be engaged by the lever, and flexible supply and discharge pipes connected to opposite ends of each cylinder. 95

2. In a washing-machine, the combination with a suitable frame, of tubs on either side 100

of the frame, cylinders mounted on the frame, pistons in the cylinders, a piston-rod rigidly connecting the two pistons, a cross-pin through the rod, a lever adapted to engage the cross-pin, flexible discharge-pipes extending from the outer ends of the cylinders to the tubs, and a flexible supply-pipe extending from

each tub to the inner end of the cylinder discharging into the other tub.

W. W. MURPHEY.
